(57) **CLAIM**

The ornamental design for an extractor socket, as shown and described.

DESCRIPTION

FIG. 1 is a perspective view of an extractor socket in accordance with an embodiment of the present invention; FIG. 2 is a top view of the extractor socket of FIG. 1; FIG. 3 is a bottom view of the extractor socket of FIG. 1; and, FIG. 4 is a side view of the extractor socket of FIG. 1. The broken lines of FIGS. 1-4 form no part of the claimed design.

1 Claim, 4 Drawing Sheets
